E. A. DIETERLE

OIL TREATING APPARATUS

Filed April 7, 1923

UNITED STATES PATENT OFFICE.

EDWARD A. DIETERLE, OF GLEN ELLYN, ILLINOIS.

OIL-TREATING APPARATUS.

Application filed April 7, 1923. Serial No. 630,431.

My invention relates to a hydrocarbon cracking apparatus the invention having for its object the provision of a construction whereby the treatment of the oil is accomplished by finely spraying the same into contact with the heated surfaces in a closed shell or casing, with the heated surfaces being preferably so arranged relative to the introduction of the oil, that the sprayed oil will 5 be progressively subjected to increasing temperatures, for the purpose of producing gasoline, or other of the lighter hydrocarbons.

A further object of the invention is to provide apparatus whereby the lighter products 15 may be withdrawn from the apparatus, while the heavier uncracked oils will separate therefrom and be withdrawn through a suitable controllable outlet.

20 A further object of the invention is to provide apparatus whereby the process of cracking may be practically continuously carried on and the serious objections heretofore encountered with the possible dangers 25 incident thereto, practically entirely eliminated, while the formation of carbon is less likely to result.

The purpose of my invention is to provide 30 a simple and efficient apparatus especially adapted to the practice of cracking oil or the treatment of tar and which at the same time may be readily cleaned, all of which purposes and advantages, as well as other advantages inherent in the construction, will 35 be more readily comprehended from the detailed description of the accompanying drawing, wherein:—

Figure 1 is a vertical sectional view of my improved apparatus.

40 Figure 2 is a vertical sectional view taken substantially on the line 2—2 of Figure 1, looking in the direction of the arrows.

In the particular exemplification of the invention, the apparatus comprises a suitable 45 metallic shell 10, of dimensions sufficient to receive a suitable number of predetermined arrangement of tubes or flues 11, 12, of material adapted to withstand the comparatively high temperatures and pressures to which 50 they are subjected in an oil cracking process and also to resist breakage that might result from temperature changes; the tubes or flues 11, 12, being preferably of calorized steel which is especially adapted to retard or prevent the 55 tendency of carbon formation.

The tubes or flues 11, 12, may be expanded

or otherwise securely fastened in the side walls of the shell or tank 10 in order to provide substantially gas-tight connection; while the ends of the flues or tubes which 60 communicate with the combustion chamber, are preferably secured in a special tube sheet as at 13, of calite or a calorized plate; and when desired the entire shell 10 may be made of calorized metal.

At a suitable point, preferably adjacent to the bottom of the shell or tank 10 and at one side thereof, I provide a combustion chamber 14, preferably containing checker brick work of suitable refractory material 70 and which is also shown provided with a suitable gas or oil burner 15, connected with a suitable source of supply which may be controlled by a suitable valve as at 16; the chamber 14 being preferably provided with 75 small openings about the burner in order to aid combustion. The products of combustion pass from the combustion chamber 14 into the various tubes or flues and discharge into the chamber 17 arranged adjacent to the 80 upper end of the shell and shown in the exemplification on the opposite side thereof, the chamber 17 being provided with a suitable stack or flue as at 18 in Figure 1.

In order to provide ample heating surface 85 and at the same time increase the length of travel of the hot gases therethrough, I prefer to bend the tubes or flues 11 and 12 back in reverse manner upon themselves with an ogee curve or into an S-formation as shown 90 in Figure 1, and to arrange the flues in series, with the flues of each series horizontally spaced apart and the flues of one series arranged in staggered relation to those of the other series. This is more clearly shown in 95 Figure 2, where the one or lowermost series for illustration, is shown comprising the two tubes 11 arranged equi-distances apart and disposed toward the opposite side of the shell where they are shown bent upwardly and in 100 reverse direction, thence upwardly and in the direction of the initial ends, as shown at 11^a. The other series is shown consisting of the three tubes or flues 12 also arranged in horizontal spaced relation but arranged 105 in vertical staggered relation with the flues or tubes 11 of the first mentioned series.

The tubes or flues 12, like the tubes 11, are provided with the reverse upward bends to provide the oppositely extending portions 12^a. With this arrangement, the hot gases 110 are not only given a circuitous or long

travel from the combustion chamber to the outlet chamber or stack, but also provide increased heating or treating surface. As is more clearly shown in Figure 2, the various bends or horizontal portions of the two series, occupy different horizontal planes, so that the oil or tar being treated will be subjected to a heated reticular surface in its passage through or path of flow into the shell.

10 The oil to be cracked is fed into the shell or tank 10, from a suitable source of supply, by means of supply pipe 19 which is shown entering the top of the shell, with the inner 15 end of the pipe provided with a suitable spraying nozzle 20; the flow through the pipe being controlled by a suitable valve as at 21.

As is clearly apparent from the construction shown, the spray of oil will contact with and pass about the uppermost turns 12^a of the series of pipes or flues 12 and the liquid or undecomposed portion will flow or drop down and contact alternately with the turns 25 11^a of the other series 11, and the next succeeding turns of each series, before the heavier or uncracked oil falls to the bottom of the shell 10.

The shell or tank 10 is preferably rectangular in cross-section and provided exteriorly with suitable insulation as at 22; and at a point adjacent to the top, the tank or shell is provided with a vapor outlet or conduit 23, whereby the vapor is led to suitable condensers and storage receptacles.

30 The heavier uncracked oil is withdrawn from the shell or tank 10 through conduit 24; the tank or shell being shown also provided with a clean-out valved opening 40 shown at 25.

In order that the condition of the tubes or flues 11 and 12 may be determined or seen, the shell 10 at a point substantially in alignment with the lower turns of the tubes 45 or flues is shown provided with a sight-cock 26; while at the same time a pyrometer as at 27, may be employed to determine the temperature.

It is apparent from the construction that 50 the injected oil spray will be subjected to gradually increasing temperatures; the lighter fractions vaporizing and rising in the shell and being withdrawn through the take-off conduit 23, to be conveyed to suitable condensers; while the unvaporized oil travels down over the tubes or flues and therefore encounters progressively hotter flues, causing other products to vaporize as the cracking progresses.

60 With my improved apparatus, it is evident that but a small amount of oil is in the system at any given time, thus materially reducing the danger of operation; while at the same time the formation of carbon is 65 less likely. In the event of any carbon being

formed, it may be readily removed by maintaining the tubes at the desired temperature while steam, superheated steam, or air is caused to pass over them; the oxygen combining with the carbon and forming carbon monoxide and dioxide, thereby removing any carbon that might form.

My improved apparatus is equally well adapted to the treatment of tar in a form that permits it to be sprayed onto or against 75 the heated flues; the essence of the invention existing in the spraying of the material onto the heated flues and preferably in a graduated manner, in order that the various products may be progressively obtained and 80 separated if desired; it being understood, however, that the tubes or flues 11 and 12 need not necessarily be provided with the curvatures shown, but that they may be differently formed and disposed intermediate 85 of the combustion chamber and the outlet or stack of the apparatus. In order that the tubes may be maintained in proper position, I prefer to provide the various supporting cross-bars 28, arranged transversely 90 of the tubes and suitably secured to the sides of the casing; and it is also apparent that a treatment of oil involving the use of a suitable catalytic medium may be practiced with my improved apparatus, as the 95 various tubes or flues may be coated with suitable catalyzing material without in any way altering the general construction of apparatus.

When desired, namely with certain oils 100 and under certain conditions, the process of decomposing or cracking the oil may be accomplished under suitable pressure in the shell by regulating the valve of outlet conduit 23 against the free flow of vapors sufficiently to produce the result desired.

It is evident that the apparatus permits of the method as heretofore described being reversed, with the oil sprayed into the tubes or flues while the heating gases or medium 110 may be caused to flow through the shell around the tubes or flues. Furthermore, the cracking of the oil may be accomplished in the presence of a suitable gas, which could be introduced into the shell in any suitable 115 manner, as for example through conduit 24 and the vapor and gas withdrawn through conduit 23; while all undecomposed or uncracked oil may be withdrawn through the clean-out opening 25; all of the methods described involving the essential step of spraying the oil into contact with suitably heated surfaces. The apparatus and method of operation have been described in terms employed merely as terms of description and 120 not as terms of limitation, as structural modifications are possible and may be made without, however, departing from the spirit of my invention.

What I claim is:—

1. An apparatus of the character described, comprising a metallic shell provided at one end with a combustion chamber while the opposite end is provided with an outlet stack, a plurality of metallic tubes or flues, bent back and forth in opposite directions, disposed intermediate of the combustion chamber and the outlet and in communication therewith, the flues being arranged in series, with the flues of one series arranged in staggered relation with the flues of the other, means communicating with a source of supply whereby oil may be sprayed onto the tubes, regulable means whereby the vaporized products may be conveyed from the shell and whereby pressure in the shell may be obtained, and means whereby the residual oils may be withdrawn from the lower end of the shell.
2. An apparatus of the character described, comprising a casing, a combustion chamber adjacent to the lower end of the casing, an outlet or stack adjacent to the opposite end of the casing, a plurality of metallic flues or tubes bent back and forth upon themselves between the combustion chamber and the stack, with one portion of a tube arranged above the other, the tubes being arranged in series occupying different horizontal planes, the tubes of one series arranged in staggered relation with those of the other, whereby a reticulate heating surface to the incoming oil is presented, means whereby a heating medium is caused to pass through said flues or tubes, means whereby the condition of said flues or tubes may be determined from the casing exterior, regulable means whereby oil may be sprayed onto said heating surface, and means whereby the separated oil products may be separately withdrawn from the casing.

EDWARD A. DIETERLE.
